UNITED STATES PATENT OFFICE.

MARTIN S. HAUGO, OF SHELLY, MINNESOTA.

SCREEN.

988,095.

Specification of Letters Patent. Patented Mar. 28, 1911.

Application filed April 25, 1910. Serial No. 557,377

To all whom it may concern:

Be it known that I, MARTIN S. HAUGO, a citizen of the United States, residing at Shelly, in the county of Norman, State of Minnesota, have invented certain new and useful Improvements in Screens; and I do hereby declare the following to be a full, clear, and exact description of the invention, such as will enable others skilled in the art to which it appertains to make and use the same.

This invention relates to improvements in screen devices for grain separators and has for an object to provide a simple, durable and inexpensive screen that may be easily mounted below the delivery worm of the grain separator, and will effectively remove wild oats and similar grains from the cleaned grain and will be so arranged relatively to the delivery worm that the latter will keep the perforations in the screen from being clogged.

A further object is to provide a screen in which the sieve member may be detached from the body of the screen by the removal of a single bolt.

With the above ends in view, the device consists of the novel construction and combination of parts hereinafter fully described and claimed.

In the accompanying drawings, forming part of this specification, Figure 1 is a fragmentary view in end elevation showing my improved screen applied to a grain separator. Fig. 2 is a plan view of the screen showing the delivery worm therein. Fig. 3 is a longitudinal sectional view through the screen. Fig. 4 is a cross sectional view taken on the line 4-4, Fig. 2. Fig. 5 is a perspective view of the screen member. Fig. 6 is a perspective view of the separate bottom plate.

Like characters of reference designate similar parts in the views shown.

The reference character 10 designates a side sill of a grain separator upon which sill is mounted a fanning mill 11 the throat of which is in registration with a plurality of horizontally disposed screens 12 through which the grain gravitates on to the inclined delivery board 13 mounted upon the side sill 10 below the throat of the fanning mill. The grain, as will be understood, is freed from chaff before it gravitates to this delivery board. The free end of this delivery board projects below the side sill and is in registration with the delivery screen 14,

forming the subject matter of this invention. The delivery screen 14 consists of a pair of parallel side bars 15 and an arcuate bottom plate 16 the sides of which are bolted or otherwise rigidly secured to the lower faces of the side bars 15 by bolts 17. Bolt openings 18 are formed in the side bars 15 to receive these bolts 17 which depend from the side sills 10 of the grain separator.

Formed in the arcuate bottom plate 16 is a longitudinal opening 20 which is sufficient in size to extend to within a short distance of the bottom faces of the side bars 15 and to within a short distance of the ends of the said bars. This construction, it is evident, forms an open bottom trough and in this trough is disposed a sieve member 21 which closes the open bottom of the trough. The sieve member consists of an arcuate perforated plate 22 the sides and ends of which overlap the sides and ends of the bottom plate 16. The perforations in this sieve are of any desired size and are preferably of sufficient size to permit of the escape of wild oats and similar small grains from the grain being advanced lengthwise of the trough by the delivery worm 23, which latter, it may now be stated is secured to the side sills 10 of the grain separator by means of suitable hangers and is of sufficient size to engage with its periphery the inner walls of the sieve member 21. Wild oats as is well known have wisps or hairs which in ordinary screens cause said oats to work into the perforations and clog the latter. The periphery of the delivery worm engaging the sieve member in this case will by rotating against the wisps of wild oat grains which have become lodged in the sieve perforations, so twist and move the wisps as to cause the grain to eventually work through the perforations and drop clear of the screen.

For securing the sieve member in position, I employ a pair of angular strips 24 each formed from a single length of material having one side portion bent abruptly at substantially right angles to the strip, as shown at 25, and thence directed in a plane substantially parallel to the main body of the strip, as shown at 26. Through the main body of each strip are formed bolt openings 27 through which the shanks of the securing bolt 28 are passed. The free legs 26 of the strip are engaged over the adjacent longitudinal edges of the sieve

2
 member 21, and secure the sieve rigidly in position. For preventing the accidental displacement of the sieve member longitudinally of the trough, I provide a retaining bolt 29, this bolt being passed transversely through registering openings 30 and 31 formed in the sieve member and bottom plate 16 and being disposed adjacent the ends of the parts so as to be conveniently reached by the operator when it is desired to remove the sieve member. It is clear that when the bolt is in position the sieve member is prevented from longitudinal movement whereby the vibration of the grain separator can not displace the sieve from position, and further, the sieve may be readily removed by simply removing the bolt.

In order that the device may be simply used as a delivery trough, I provide a separate bottom plate 32 which is arcuate in contour and is preferably identical in size with the above-mentioned sieve member. The separator bottom plate may be inserted lengthwise of the bottom plate 16 and its side edges engaged beneath the outstanding free legs of the before-mentioned clamping strips 24. An opening 33 is disposed in the separate bottom 32 and receives the bolt 29 when the separate bottom has reached its final position.

It is clear that a delivery trough constructed as above described may be changed from an ordinary delivery trough to a screen delivery trough with very little labor and inconvenience as the securing bolt 28 is disposed within convenient reach of the operator, with very little discomfort to the operator.

From the foregoing description taken in connection with the accompanying drawings, it is thought the construction and operation of my invention will be easily understood without a more extended explanation, it being understood that various changes in the form, proportion and minor details of construction may be made within the scope of the appended claim.

What is claimed is:—

The combination with a grain separator side sills, delivery board, and delivery worm of a pair of approximately parallel cross bars spanning said sills and underlying the discharge end of said delivery board, an outwardly bowed plate having its longitudinal edges secured to the cross bars, and having a longitudinal opening extending in all directions nearly to the marginal edges of the plate, a screen housing said delivery worm and conforming to the inner contour of the plate, and further having its borders bearing upon the marginal portions of said plate, guide members carried upon the inner faces of said cross bars and having portions overlying and loosely engaging the marginal portions of said screen, said guide members being spaced from and confronting the edge of said delivery worm, and a locking pin removably engaged through the over-lapping portions of the screen and plate.

In testimony whereof, I affix my signature, in presence of two witnesses.

MARTIN S. HAUGO.
